UNITED STATES PATENT OFFICE.

LEO J. WAHL, OF STERLING, ILLINOIS, ASSIGNOR TO WAHL CLIPPER CORPORATION, OF STERLING, ILLINOIS, A CORPORATION OF ILLINOIS.

SELF-REGULATING DEVICE FOR ELECTROMAGNETIC CLIPPERS.

Application filed October 16, 1925. Serial No. 62,806.

My invention relates to a self-regulating device for regulating the power of electro-magnetic clippers.

It is a purpose of my invention to provide means whereby the power obtained from an electro-magnetic clipper is substantially uniform even though the voltage impressed on the electro-magnet varies. This is accomplished by providing a core that is unsymmetrical relative to the coil of the electro-magnet and means resisting movement of said coil in one direction so that an increase in the voltage of the energizing current moves the coil against the resistance of said means to increase the self-inductance thereof, while a decrease in voltage will cause said means to move the coil in the opposite direction to decrease the self-inductance, it being obvious that said means can be so adjusted that the movement of the coil will be such that the effect of the change in self-inductance will counter-balance the effect produced by the change in voltage so that the power obtained from the electro-magnet will be substantially uniform.

More particularly it is a purpose of the invention to provide an electro-magnet having a core extending through the coil thereof that has a relatively large mass of iron at one end of the core, the coil being movable on the core toward and away from said end having the large mass of iron and to provide resilient means counteracting the movement of the coil toward the larger mass of iron to thus provide substantially uniform power obtainable from the electro-magnet. It is well known that when the voltage increases, the tendency of the coil to move further onto the core toward the large mass of iron will increase. By adjusting the tension of the resilient means, this tendency can be counteracted in such a way that the movement toward the larger mass of iron will be at such a rate that the increase in self-inductance brought about by the approach of the coil toward the large mass of iron will be just enough to decrease the power of the electro-magnet as much as the increase in voltage would otherwise have increased the power of said electro-magnet, thus providing an electro-magnet that has substantially uniform power. This is quite important in view of the fact that the voltage varies considerably on the lines of central station systems. If the voltage in-

creases, and the power becomes too great, the armature will be drawn against the core or against a suitable stop member with such force as to produce a chattering of the clipper. While if the device is so adjusted that this will not occur when an increase in voltage takes place, the normal voltage will be insufficient to efficiently operate the movable blade of the clipper. Preferably, the mass of iron is provided by a cross piece on the core which also serves the function of providing a path for the magnetic flux from the central portion of the core at the one end of the coil toward the movable element or armature.

The arrangement whereby the power of the electro-magnet is adjusted due to the movement of the coil on the core is of great advantage over the methods previously used due to the fact that such methods usually constituted movement of the armature relative to the core to vary the gap between the core and the armature which resulted in undue heating of the electro-magnet upon an increase in voltage, as the magnetic resistance was also increased simultaneously with the increase in voltage.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a vertical section of a clipper partly in elevation embodying my invention; 95

Fig. 2 is a top plan view partly in section of said clipper, a portion of the cover being broken away;

Fig. 3 is a section taken substantially on the line 3-3 of Fig. 2; and 100

Fig. 4 is a plan view of the core.

Referring in detail to the drawings, my improved clipper construction comprises a casing 10 having the cover 11, said casing having the stationary clipper blade 12 secured thereto. Cooperating with the stationary clipper blade 12 is a movable clipper blade 13 that reciprocates transversely of the blade 12. The connecting bracket 14 forming a part of the movable element of 110

the clipper connects the blade 13 with the armature 15 which is connected at 16 with a resilient member 17 that is clamped to the casing by means of the securing means 18 and is adjusted transversely by means of the screw 19 so as to obtain the proper positioning of the blades 12 and 13 relative to each other.

The vibratory member comprising the elements 14, 15 and 17 is vibrated by means of an electro-magnet comprising a coil 20 which is movably mounted on the central tapering portion 21 of a core having a cross member 22 thereon extending transversely 15 of said coil 20 at one end of the core 21 and terminating in ears 23 extending on opposite sides of the coil 20 through which the securing devices 24 extend for securing the core in position in the casing 10.

20 It will be noted that the ears 23 forming the ends of the core at opposite sides of the coil 20 extend toward the connecting portion 16 and the inward offset 25 in the member 15 to thus provide a path for the magnetic 25 flux that has but a very small amount of air gap. It will also be noted that the central core portion 21 is smaller at the end thereof remote from the cross piece 22 gradually increasing in size toward said cross piece.

30 It will also be noted that the cross piece 22 is of greater thickness than the central portion 21 so as to provide the proper amount of iron in this portion of the core. The coil 20 is free to slide axially along the core portion 21 and is provided with the end members 26 and 27, the end member 27 having openings therein for receiving the fingers 28 provided on the end piece 29 connected with the coil spring 30, the opposite end 40 of which is seated within the bore 31 provided in the hollow screw-threaded adjusting nut 32 which screw-threadedly engages with a screw-threaded opening 33 in the casing 10. The member 27 is preferably 45 provided with an ear 34 depending therefrom with which the member 29 engages. The adjusting nut 32 may be knurled if desired and extends outwardly from the casing, as clearly shown in Figs. 2 and 3 so that 50 adjustment of the same can be made from outside the casing 10 without removing the cover 11. The spring 30 is a compression spring and it will be obvious that by turning in the screw-threaded member 32, the tension of the spring 30 can be increased and vice versa. The spring 30 resists the movement of the coil member 20 toward the end 55 of the core 21 that is provided with the cross piece 22.

60 When an increase in the voltage occurs, the coil 20 will tend to move on the core toward the cross piece 22 thereon. The spring 30 will tend to resist such movement and it

will be evident by proper adjustment of the spring resistance that such movement can 65 be regulated so that the movement will be in such proportion to the increase in voltage that the increase in self-inductance due to the approach of the coil 20 to the cross member 22 will counter-balance the effect of the 70 increase in voltage so that the power of the electro-magnet exerted on the vibratory member will be substantially uniform, thus avoiding any variation in the operation of the movable clipper blade due to the changes 75 in voltage. By tapering the portion 21 of the core, the coil 20 will tend to center itself as it moves toward the cross piece 22, and the mass of the same also increases progressively toward the cross piece 22. 80

Having thus described my invention, what I desire to claim and secure by United States Letters Patent is:

1. In a device of the character described, an electro-magnet comprising a coil, a core 85 extending through the same, said core having a relatively large mass of iron at one end thereof and an armature contacting face at the other end thereof and said coil being movable on said core toward and away from 90 said mass thereof, and adjustable means for yieldingly urging said coil away from said mass.

2. In a device of the character described, a frame, an electro-magnet comprising a 95 coil, a core extending through the coil and fixed to said frame, said core having a relatively large mass of iron at one end thereof and said coil being movable on said core toward and away from said end thereof, 100 whereby an increase in voltage tends to move said coil toward said end of said core, resilient means yieldingly resisting said movement, and means on said frame for adjusting the tension of said resilient means. 105

3. In a device of the character described, a core having a contact face at one end thereof and an enlarged transversely extending portion at the other end thereof, an armature movable toward and away from 110 said contact face, a coil on said core movable endwise thereof and resilient means pressing said coil toward said armature.

4. In a device of the character described, a core having a contact face at one end thereof and an enlarged transversely extending portion at the other end thereof, an armature movable toward and away from 115 said contact face, a coil on said core movable within fixed limits endwise thereof, resilient means pressing said coil toward said armature and means for varying the pressure of 120 said resilient means against said coil.

In witness whereof, I hereunto subscribe my name this 1st day of Oct., A. D. 1925.

LEO J. WAHL.
